UNITED STATES PATENT OFFICE.

MAX ARNDT, OF AIX-LA-CHAPELLE, GERMANY.

AIR OR VACUUM MOTOR.

SPECIFICATION forming part of Letters Patent No. 714,273, dated November 25, 1902.

Application filed January 20, 1899. Serial No. 702,855. (No model.)

To all whom it may concern:

Be it known that I, MAX ARNDT, a subject of the King of Prussia, German Emperor, residing at the city of Aix-la-Chapelle, Germany, 5 have invented a new and useful Improved Air or Vacuum Motor, (for which has been filed an application for Letters Patent in France June 24, 1898, and in Germany June 23, 1898,) of which the following is a specification.

10 My invention relates to an air or vacuum motor and to be actuated by slight pressure—as, for instance, the draft of a smoke-stack.

15 My invention consists of a bell dipping into a locking liquid and suspended on a fulcrum lever, of an aspirator, ventilator, and the like, or with a blast or a smoke stack communicating with the bell by a pipe discharging into the interior of the bell, of a valve located on the said pipe, and of the valve-actuating device connected with the said lever.

20 In the accompanying drawings I have represented my invention.

Figure 1 is a view and partial section of the apparatus. Fig. 2 is a view of the apparatus 25 connected with a stack on a reduced scale.

20 A ring-shaped vessel, consisting of walls a' and a^2 , is mounted on legs v to contain a locking liquid b in the annular space a , and a bell c dips into that liquid, the bell being suspended by a rod s' on a two-armed lever h , pivoted at m . Lever h is provided with a counterweight g and with pins i' i^2 on a segment i , fixed to the lever.

35 A pipe d' discharges into the interior of bell c and is connected to a pipe d^2 by a connection pipe or hose d^3 . Pipe d^3 is provided with a hollow stub d^4 of comparatively small diameter, which latter is to be connected by a hose or pipe with the source of the driving force—40 say a smoke-stack, an aspirator, ventilator, and the like, or with a blast.

45 A valve e is secured at the upper end of pipe d^2 and fixed to a lever f , pivoting on stud n and carrying a counterweight f' . Lever f is provided with two abutments f^2 f^3 to engage alternately with the bent end k^2 of a controlling-lever k' , pivoting on m and carrying a weight k^3 . As lever h is reciprocated lever k' is alternately struck by the pins i' 50 and i^2 and accordingly swung toward the left and toward the right, thus alternately

engaging by its end k^2 with abutments f^2 and f^3 , so as to temporarily open and close valve e .

The operation of my invention is as follows: Supposing stub-pipe d^4 connected with a 55 smoke-stack and valve e closed, the air within bell c will be sucked and the latter accordingly lowered, taking along with lever h against the pressure of counterweight g , the pressure difference within bell c being at the 60 same time balanced by a liquid column H rising above the level of the external liquid. As lever h performs its stroke controlling-lever k' will be struck by pin i' so as to swing toward the left under the influence of weight 65 k^3 and open valve e . In consequence thereof the sucking action of the smoke-stack with respect to the interior of bell c will be interrupted and atmospheric air is sucked through the open upper end of pipe d^2 ; but as pipe d^4 70 is of a comparatively small size with respect to pipe d^2 , as stated heretofore, but a small portion of air will be practically sucked through pipe d^4 , and the main portion of the air entering through pipe d^2 flows through 75 pipes d^5 d^6 to the interior of bell c , restoring the atmospheric pressure within the latter. Bell c will therefore be raised again under the influence of weight g and lever h accordingly swung back until pin i^2 strikes against 80 controlling-lever k' , causing the same to swing toward the right, so as to close again valve e , and so on. The swinging movement of lever h may be transferred by any convenient means—say, for instance, by a rod s^2 . 85 The rod s^2 can be connected with a crank for driving a shaft or the rod s^2 can move a piston of a pump. In connecting pipe d^4 with a source of compressed air—a blast, for instance—the controlling action of lever k' is 90 simply to be inverted, so as to open the valve during the upward movement of the bell, (which is effected by the compressed air entering the interior of the bell,) and so close it during the downward movement of the bell 95 after the compressed air has been discharged.

What I claim, and desire to secure by Letters Patent, is—

In a motor the combination with a smoke-stack of a bell dipping in a sealing liquid and suspended on a counterweighted lever, a main pipe discharging into the interior of the bell 100

and connected with the smoke-stack by a branch pipe of a comparatively small size, a valve to temporarily open and close the main pipe and a controlling-lever actuated by the 5 said counterweighted lever to control the valve.

In testimony that I claim the foregoing as

my invention I have signed my name in presence of two subscribing witnesses.

MAX ARNDT.
